FRED VANCE McDONNELL, OF LOGANSPORT, INDIANA.

LIFTING-JACK.

1,111,614.

Specification of Letters Patent.

Patented Sept. 22, 1914.

Application filed March 9, 1914. Serial No. 823,401.

To all whom it may concern:

Be it known that I, JAMES PILLING RENEKER, a citizen of the United States, and a resident of Logansport, in the county of Cass and State of Indiana, have invented a new and Improved Lifting-Jack, of which the following is a full, clear, and exact description.

This invention relates to hoisting and has particular reference to lifting jacks of the screw type and adapted to be operated especially by power motors for lifting heavy weights such as locomotives and cars for the removal of wheels and trucks.

15 Among the objects of the invention is to provide automatic cut-outs or releasing devices to prevent damage to any part of the mechanism at the upper or lower limits of movement of the lifting screw.

20 Another object of the invention is to provide automatically operated connecting and disconnecting means whereby the power screw is reversed directly as to its operation by the simple reversal of the prime mover.

25 Another object of the invention is to construct a device whereby certain reversing features are produced by the use of pawls which are thrown into or out of positive operation by frictional contact with other parts whereby the necessity for using springs is avoided for such purposes. By this means unnecessary noise and wear and tear upon the parts are reduced to a minimum.

35 The foregoing and other objects of the invention will hereinafter be more fully described and claimed and illustrated in the drawings forming a part of this specification in which like characters of reference 40 indicate corresponding parts in all the views, and in which—

Figure 1 is a vertical sectional view of a device made in accordance with this invention and indicating the relation of the parts 45 while the weight is being lifted; Fig. 2 is a similar view showing the parts in the positions assumed thereby when the upper limit of movement is reached and the automatic cut-out is made effective; Fig. 3 is a 50 plan view of the device; and Figs. 4, 5, 6, 7 and 8 are transverse sections on the corresponding lines of Fig. 1 and looking in the directions of the arrows.

The several parts of this device may be 55 made of any suitable materials, and the

relative sizes and proportions, as well as the general design of the mechanism, may be varied to a considerable extent without departing from the spirit of the invention hereinafter more fully set forth and specifically claimed.

By way of an illustration of a preferred embodiment of this invention, I show a base 10 having a rigid hollow pedestal 11, extending upwardly therefrom, of cylindrical form and carrying at its upper end a main power nut 12, the same being secured in fixed position to the upper end of the cylindrical pedestal 11 by means of coöperating shoulders and set screws 13. The nut 12 has an outwardly projecting flange 14 at its upper portion and said flange is provided with vertical oppositely spaced slots or holes 15. The other main portion of the jack comprises a casing 16 slidable vertically on 70 the outside of the pedestal 11 and nut 12. The main or lower portion of the casing 16 is in the nature of a hollow cylinder and is slidably fitted for movement along the edge of the flange 14 of the nut, said flange 75 constituting, therefore, a centering device for the casing. The lower end of the casing, being spaced from the outer surface of the pedestal, is provided with a collar 17 secured in place by screws 18, and said collar 80 17 constitutes a guiding and centering device for the lower end of the casing as it operates upwardly and downwardly along the pedestal.

The upper end of the casing 16 is flared 90 outwardly and has secured to it a head 19 by means of a series of bolts 20 operating through coöperating flanges 21 of the casing and head. The main power devices of the jack are housed within the space below 95 the head or between the head and the flared portion of the casing. The weight to be lifted or lowered is supposed to be engaged directly by the roughened surface 22 of the head.

The main lifting screw 23 is arranged 100 within the casing below the head 19 and has direct positive coöperation with the nut 12, suitable means being provided to rotate the screw, causing it to move upwardly and 105 downwardly within the nut. At 24 I show a power spindle journaled in a bearing 25 formed in the flanges 21 of the casing and head, the axis of the spindle being preferably horizontal and at right angles to the 110

axis of the screw. The spindle is intended to have attached to it any suitable prime mover such as a pneumatic engine or electric motor, the connection being by means of a flexible shaft (not shown), but whereby the spindle 24 may be driven positively in either direction both for hoisting and lowering a load carried by the top of the head. The head of the spindle 24 within the casing is provided with a bevel pinion 26 meshing with a gear 27 journaled for free rotation around the axis of the screw. The screw is shown provided with a reduced upper end 28 forming an annular shoulder 29 upon which is seated a hub 30 which normally rotates with the screw. Located above the gear 27 and the hub 30 is a spur gear 31 separated from the hub 30 by a plurality of antifriction rollers shown as balls 32. The gear 27 has journaled in it a plurality of vertically arranged shafts 33 shown as four in number and spaced equally from one another at 90 degrees around the axis of the spindle 28. Each of said shafts 33 carries at its upper and lower ends a pair of pinions 34 and 35, the upper pinion 34 being larger than the lower pinion 35 by one or more teeth. The upper pinions 34 all mesh with the normally stationary fulcrum gear 31 above referred to, and the pinions 35 all mesh with a driven gear 36 surrounding the lower portion of the hub 30 and resting upon a driving disk 37 keyed or otherwise rigidly secured to the lifting screw. The gear 36 has an outwardly extending flange 38 to which are pivoted a plurality of reversing pawls 39, said pawls having frictional engagement with the upper surface of the driving disk 37. As shown in Fig. 7, said pawls 39 are adapted to nest inwardly within the outline of the flange 38 when the jack is operating to lift the head, but when the screw is to be operated in the opposite direction the pawls are carried outwardly by frictional contact with the driving disk so as to engage lugs 40, as shown by dotted lines in Fig. 7.

The fulcrum gear 31 has secured to the upper surface thereof a ratchet disk 41 with which a plurality of pawls 42 are adapted to coöperate, and said ratchet disk carries on its upper surface a friction plate 43 adapted to bear directly against the lower surface of the top of the head when the load is being lifted. Under these conditions the pawls 42 positively prevent rotation of the ratchet disk and fulcrum gear, these parts being connected by fixed screws 44. Since the fulcrum gear 31 is held stationary, as just stated, for the purpose of hoisting the load, the gear 27 being driven by the pinion 26 in the direction indicated in Fig. 5, the several pairs of gears 34 and 35 will be carried around the fulcrum gear 31, and the gear 36 will be caused to rotate slowly around

the hub 30 due to the comparatively slight disparity in diameters of the pinions 34 and 35. The smaller the difference between the number of teeth on these two pinions, the slower will the gear 36 be driven. I provide, therefore, a means whereby a comparatively rapid running motor with a corresponding rotation of the shaft 24 may be caused to produce a slow movement of the gear 36 with a corresponding high power. The gear 36 is caused to be clutched to the driving gear 37 by any suitable detachable means. For this purpose I employ a plurality of clutch pins 45 which are secured to and carried by a clutch collar 46 which surrounds the screw below the driving disk 37. These clutch pins extend upwardly through holes in the driving disk and extend normally into holes or sockets formed in or through the gear 36 or its flange 38. Said clutch collar is carried by a sleeve 47 surrounding the screw and normally rotatable therewith due to the action of the pins, and said sleeve is held forced upwardly normally by means of a helical spring 48 operating between the sleeve 47 and a collar 49 adjustably secured to the body of the screw. The driving disk 37 is secured to the screw directly above a supporting shoulder 50. The sleeve 47 is provided with an outwardly projecting flange 51 between which and the clutch collar 46 is secured a ring 52, antifriction rollers being provided between the collar and flange 51. The ring 52 has connected to it by bolts 53 a pair of straps 54 which extend downwardly through the above described slots 15 in the nut flange. The lower ends of said straps are secured rigidly and permanently in any suitable manner as by rivets to a ring 55 which surrounds the pedestal closely above the guide ring 17, and a cushion device, shown as a ring of flexible rubber 56, coöperates with the upper surface of said ring 55. The rings 52 and 55 with their connecting straps 54 are normally non-rotary but slide upwardly and downwardly substantially in the same manner as does the casing during the operation of the screw.

Having now set forth the description of the principal parts of the mechanism, a brief description of the method of operation will now be given:—Rotation of the driving shaft 24 will cause the gear 27 to rotate around the axis of the spindle 28 and fulcrum gear 31, and the gear 36 will be driven in the same direction but at a slow speed due to the differential pinions 34 and 35. The clutch pins 45 being in the position shown in Fig. 1 will cause the rotation of the driving disk 37 and screw 23 simultaneously with the movement of the gear 36. The nut 12 being stationary, rotation of the screw in the manner stated will cause it to

be unscrewed upwardly along or through the nut, lifting a load resting upon the top of the head. The antifriction rollers 32 will act to take the main frictional strain between the stationary and rotating parts. After the load is lifted and it is desired to lower it to remove the jack, reverse rotation of the driving shaft 24 will reverse the action of the gears and screw, causing the load to be lowered, the spring 48 acting normally in this connection to hold the clutch pins in engagement. If, however, the operation of the power shaft is continued so as to hoist the casing to the upper limit of movement, I provide a means whereby the connections will prevent the continued rotation of the screw, thereby avoiding any damage or breakage of any of the parts. As shown in Fig. 2, when the screw is lifted as high as it ought to go, the ring 55 through its cushioning ring 56 engages the lower surface of the flange 14 of the nut, and this action through the straps 54 and ring 52 will draw the clutch collar 46 downwardly away from the driving disk 37 and withdrawing the pins 45 from the driving gear 36. As soon as the connection is broken by this means between the gear 36 and driving disk 37, and the friction is relieved between the pins 45 and the driving disk, the cushioning ring 56 due to its resiliency will immediately cause the pins to be further withdrawn from the driving gear 36. The gear 36 may now be free to rotate under the continued movement of the motor without danger of injuring the machine, and, of course, without affecting the screw. The load, however, will be held by the screw as usual. When the load is to be lowered there may be given a reverse rotation of the power shaft 24 and corresponding rotation of the gearing, the friction between the head and the ratchet disk 41 being maintained momentarily so as to hold the fulcrum gear 31 stationary, and the rotation of the driving gear 36 in the opposite direction will cause, as stated above, the pawls 39 to be carried outwardly by friction into engagement with the lugs 40 whereby the driving disk will be rotated positively and independently of the clutch pins until the screw is turned downwardly far enough for the connection to be re-established between the gear 36 and disk 37 by the pins 45, due to the action of the spring 48.

In case the motor continues to operate after the casing 16 reaches its lower limit of movement, the power connections will be separated, due to the fact that the lower end of the casing will strike against the shoulder 10' of the base and the slight further movement of the screw will carry the bottom of the friction disk 37 into frictional contact with the shoulder 37' of the flared portion of the casing. The load will

then be supported directly through the casing upon the base and the amount of clearance which normally exists between the disk 37 and the shoulder 37' will be transferred, so to speak, between the top of the head 22 and the friction disk 43, allowing the ratchet disk 41 and fulcrum gear 31 to rotate idly, the disk passing the pawls 42. Therefore, the driving gear 36 remains stationary and no injury may result to the mechanism, even though the motor may continue to run for a time. When the power is again reversed to lift the load from the base, the pawls 42 will again be made functional to hold the fulcrum gear 31 stationary and the operation will proceed as already disclosed. The casing may be provided with any suitable number of handles, as indicated at 57.

Having thus described my invention, I claim as new and desire to secure by Letters Patent:

1. In a power operated lifting jack, the combination of a base including a pedestal, a casing movable vertically along said pedestal and including a load supporting head, a power shaft journaled in the casing, a lifting screw within the casing and coöperating with the pedestal, clutch connections between the power shaft and the screw, and means to automatically stop the rotation of the screw when the casing reaches its upward limit of movement independently of the stoppage of the power shaft.

2. In a power operated lifting jack, the combination of a base including a pedestal, a casing movable vertically along said pedestal and including a load supporting head, a power shaft journaled in the casing, a lifting screw within the casing and coöperating with the pedestal, clutch connections between the power shaft and the screw, and means to automatically stop the rotation of the screw when the casing reaches its lower limit of movement independently of the stoppage of the power shaft.

3. In a power operated lifting jack, the combination of a base including a pedestal, a casing movable vertically along said pedestal and including a load supporting head, a power shaft journaled in the casing, a lifting screw within the casing and coöperating with the pedestal, clutch connections between the power shaft and the screw, and means to automatically stop the rotation of the screw when the casing reaches either its upper or lower limit of movement.

4. In a lifting jack, the combination of a base including a vertically extending pedestal, a casing including a load supporting head movable vertically with respect to the base, a rotary screw within the casing through which the casing is hoisted upon the pedestal, a driving disk secured to the screw, a power shaft journaled in the casing, reduction gearing between the power shaft and

the driving disk, shiftable means connecting the driving disk to the last element of the reduction gearing adjacent thereto, and means acting between the pedestal and the shiftable means to disconnect the same from the gearing when the screw is run to its uppermost limit.

5. In a lifting jack, the combination of a base, a casing movable upwardly with respect to the base and including a load supporting head, a power shaft journaled in the casing, gearing within the head operated by said power shaft, a screw coöperating with the base and clutched normally to said gearing, said gearing including a fulcrum gear, means to hold the fulcrum gear from rotation while the load is being hoisted, and means to automatically disconnect the clutch aforesaid when the screw and casing reach 20 their upper limit of movement.

6. In a lifting jack, the combination of a base, a casing movable upwardly thereover and including a load supporting head, a power shaft journaled in the casing, gearing connected to said power shaft and housed within the head, said gearing including a fulcrum gear, friction means between said gear and the head whereby the fulcrum gear is held stationary at certain times, a screw within the casing and associated with said gearing, and selective shiftable clutch connections between the gearing and the screw.

7. The combination of a base, a power screw operating upwardly with respect to said base, a casing surrounding the screw and including a load supporting head, reduction gearing within the head, selective

shiftable clutch mechanisms between the gearing and the screw, said clutch mechanisms including a driving gear, a driving disk, and movable members acting between said gear and said disk.

8. In a lifting jack, the combination of a load supporting member, a power shaft, 45 gearing within the load supporting member in operative connection with said power shaft, a screw associated with said gearing, a driving disk secured to the screw and supporting the last element of the reduction 50 gearing, a pawl pivoted to the driving gear on an axis parallel to the screw and having frictional contact with the driving disk and thereby thrown into engagement positively with said disk at times, and frictional means 55 to stop the rotation of the driving disk automatically when the load supporting head reaches its lower limit of movement.

9. In a lifting jack, the combination of a base, a rotary screw coöperating with the 60 base, a casing including a load supporting head surrounding the screw, a driving member, gearing within the head operated from said driving member in either direction to run the screw up or down, one member of 65 the gearing having frictional engagement with the load supporting head, and detachable clutch connections between another part of the gearing and the screw.

In testimony whereof I have signed 70 my name to this specification in the presence of two subscribing witnesses.

JAMES PILLING RENEKER.
